UNITED STATES PATENT OFFICE.

DOMENICO RONCONI, OF CHICAGO, ILLINOIS.

VALVE MECHANISM.

1,241,662.

Specification of Letters Patent.

Patented Oct. 2, 1917.

Application filed January 18, 1917. Serial No. 143,066.

To all whom it may concern:

Be it known that I, DOMENICO RONCONI, a subject of the King of Italy, at present residing in Chicago, in the county of Cook 5 and State of Illinois, have invented a new and Improved Valve Mechanism, of which the following is a specification.

My present invention, which in its general nature has reference to improvements on the 10 valve mechanism especially adapted for use in internal combustion engine structures, more specifically seeks to provide an improved oscillatory valve mechanism of that type shown and described in my copending 15 application, Serial No. 130,873, filed November 11, 1916, to which my present improvements especially apply.

Among other objects, my present invention has for its purpose to provide an improved construction of the valve member, the seat on which it oscillates and the means 20 effecting the oscillation thereof, whereby a less number of parts are needed for actuating the valve and the operation thereof is 25 rendered the more silent and positive for the shifting durations required.

Another object of my present invention is to provide an improved oscillatory valve 30 structure of the general type referred to in which the parts are particularly designed for providing an improved self-grinding valve and a coöperative valve seat construction, by which the fitting of the valve and its seat 35 is easily effected and rendered positive and noiseless in its action.

With other objects in view that will hereinafter appear, my present invention is an improved valve mechanism of the general character stated, that comprises the peculiar 40 features of construction and novel coöperative arrangement of parts that will be first explained in detail, specifically pointed out in the appended claims and illustrated in the accompanying drawings, in which:

45 Figure 1 is a vertical section of my improved valve mechanism, so much of the head portion and the cam shaft of an internal combustion engine being shown, as is necessary to illustrate a practical application 50 of my invention.

Fig. 2 is a top plan view thereof, the upper or cap portion of the engine head being omitted.

55 Fig. 3 is a transverse section of my new valve mechanism taken on the line 3—3 on Fig. 1.

Fig. 4 is a diagrammatic plan view that illustrates the coöperative arrangement of the shaft actuated rotary cam devices and the cam device on the valve stem, herein- 60 after specifically referred to.

Fig. 5 is a top view of the valve seat.

Fig. 6 is a perspective view of one of the valve stem oscillating cams.

Fig. 7 is a perspective view of the check 65 or stop device for restricting the oscillations of the valve.

Fig. 8 is a vertical section of a modification, hereinafter referred to.

Fig. 9 is a plan view of a modified form 70 of the oscillatory valve.

Fig. 10 is a similar view of a modified form of seat plate for coöperating with the said valve.

In the practical application of my present 75 invention, in the general arrangement thereof, the same is combined with the engine cylinder in a manner similar to the arrangement of the valve mechanism disclosed in my copending application, before 80 referred to.

It should be here stated that the valve in the construction shown in my copending application, of the oscillatory type, is oscillated or turned in one direction by mechanism actuated by power transmission from the engine shaft and it is pulled or oscillated back in the other direction, by other means not actuated by the engine shaft power. 90

The seat 2, in my present construction of valve mechanism, is removably mounted on a sub-seat 2^a that forms the bottom of the valve chamber 6 and, which, has the intake (or exhaust) manifold duct R. 95

The valve seat 2 includes a hollow stem which constitutes a bushing and which extends down through a hub 2^b and the lower end of such hollow stem projects below the hub 2^b and has external screw threads 16, 100 as is clearly shown in Figs. 1 and 3 in which is also indicated the position of a stopping device 12, the detail construction of which will presently more fully appear, a lock nut 14 and a jam nut 13, the latter being provided for holding the valve seat tightly to its seat. 105

The stopping device 12 which is shown in detail in Fig. 7, includes an apertured ring like body 12^a that fits over the stem 1^a and a 110 segmental extension 34, the opposite edges of which terminate in pendent stop lugs 35

that coöperate with a screw pin 37 which passes through the valve stem 1^a, as shown, and to hold the device 12 to its proper operative position, a pin 15 passes up through an aperture 33 therein and into a corresponding aperture 33^a in the valve casing, as is clearly shown in Fig. 1.

3 designates what I hereinafter term the double cam and the said cam is fixedly held on the squared lower end of the valve stem by lock nut 26 and cotter pin 27.

10 A light tension coil spring 17 is held about the valve stem between the valve chamber hub and the cam 3 and which tends to at all times hold the valve against its seat.

15 18 designates what is hereinafter termed the cam shaft upon which are adjustably mounted a pair of cams 4 and 5 which operate for oscillating the valve to the opening and closing positions.

20 The valve opening cam 5 includes a segment shaped lug or shoulder 6 at the peripheral edge thereof and a central hub like member 19—19 and the closing valve 4 has a like shaped lug 7 and a hub portion 19, as is clearly shown in Fig. 1 from which it will also be seen that each of the said cams 4 and 5 has an outwardly extended flange 21 formed with an elongated slot 21^a whose opposite side edges have semi-circular indentations 22 adapted for being brought into register with a corresponding aperture 18^a in the squared portion of the cam shaft 18 and which receives lock pins or bolts 50—50, it being understood that the cams after they are moved along the shaft to the desired adjustment may be locked to such adjustments by passing the bolts 50 into the holes 18^a and in engagement with the coincident indentations 22, as shown.

40 To provide for maintaining a positively rigid relation of the oppositely disposed cams 4 and 5, spacers in the nature of thin washers 20 are located on the shaft 18 between the adjacent ends of the cam hubs 19 and to provide for conveniently applying or removing them, the said washers are of the peculiar design illustrated in Fig. 3, which shows the washers as having an aperture 28 for the passage of one of the tie bolts 23, four of which are preferably used, and pass through the cams 4 and 5 and the spacer washers 20, as is clearly shown in Fig. 1, and to provide for fitting the washers over the shaft 8 onto a pair of opposite ones of the bolts 23, the washers are each formed with a slotway 30 and lateral notches 29.

60 To accomplish the desired result and to prevent the valve stem cam from going out of proper line of action the oppositely projected wings or projections *x* and *y* of the said cam are relatively disposed at predetermined angles, for example, 178° to 120°, depending upon the oscillatory or timing operations to be given to the said valve.

70 One of the essential features of my present invention is that the operation of oscillating the valves is a positive and a practically noiseless one, since the opening and closing cams are so mounted upon the cam shaft that after the opening cam has shifted the valve to open the valve port to the port R and breaks contact with the double stem now holding the valve to its last shifted or open position, and with the cam 3 in position for being engaged by the closing cam 4, that follows the cam 5, and by which the valve is now oscillated to the opposite or closing position where it is again held under its spring tension until the cam 3 is next engaged by the opening cam 5.

75 The timing of the means for oscillating the valve in my present valve mechanism is readily accomplished by reason of the manner in which the cams 4 and 5 are adjustably mounted on the cam shaft, as hereinbefore described.

80 To provide for the desired adjustments to produce the predetermined timing of the opening and closing operations, for the intake or exhaust valve devices, it is only necessary to loosen the bolts 23 sufficiently that one or more of the spacer washers 20 may be pulled out and corresponding adjustments made of the parts 21 and 22, 90 should such parts be used in conjunction with the spacer washers 20, it being understood that it is not absolutely necessary to use the bolt locks 50 when the washers 20 are employed.

100 By removing one or more of the washers 20, the two cams 4 and 5 may be readily moved closer to each other and by reason thereof, an increased time of contact with the cams 4 and 5 and the double cam is provided for, it being obvious that by adding washers 20, the cams 4 and 5 will be relatively further separated and in consequence reduce the time in which the cams 4 and 5 remain in contact with the valve cam 3 during the rotary motion of the said cams 4 and 5 with the cam shaft, and, at this point, it should be stated that in the practical application of my present invention, the cam shaft is geared with the crank shaft so that it makes a half revolution at each complete revolution of the crank shaft.

110 In Fig. 8, I have illustrated how my present valve arrangement can be applied to any puppet valve motor now in use, thus transforming such motor into one having silent and self-grinding valves.

120 In this latter form, Z designates the valve seat, 10 a gasket applied next to the seat which may be oiled from a pipe coming from a level system and oil grooves 31—32 communicating with each other in any suitable manner.

125 The slot 36 in the check device, hereinbefore referred to, in practice, is of such 130

width that it prevents the valve from going beyond the working line as it is oscillated and, at the same time, is sufficient to allow for the desired adjustments of the cams 4 and 5 for a wider or closer movement limit of the valves.

In my present construction of valve mechanism, the springs, rods and link connections required in my other structure shown in my 10 copending application, are dispensed with; the mounting of the valve is such that it is a self-grinding one and one that is maintained under such tight closure that a higher engine efficiency from the working agent is obtained with a material reduction in gas 15 consumption.

Instead of forming the valve and the valve seat with but a single port, as indicated in Fig. 2, the valve may be formed with two 20 diametrically opposite ports or orifices, as indicated at 25, in Fig. 9, for coöperating with similarly arranged ports 25^a—25^a in the valve seat shown in Fig. 10.

By providing a plurality of ports in the 25 valve and the seat arranged as stated, larger total ports are provided for my rotary valve mechanism, particularly when the same is to be applied to puppet valve motors.

From the foregoing description taken in 30 connection with the accompanying drawings, it is thought the complete construction, operation and advantages of my invention will be readily understood by those skilled in the art.

35 What I claim is:

1. In a valve mechanism of the character described, the combination with a cylinder, a casing having a valve seat including a hollow stem and a port in communication 40 with the compression end of the cylinder above the valve seat, a fluid passage for connection with the intake or exhaust manifold of the engine and a port in the valve seat in connection with the said fluid 45 passage; of an oscillating disk valve, said valve including a stem that passes through the valve seat stem mounted upon the valve seat, means for holding the valve to the seat, engine power controlled means for 50 intermittently oscillating the valve to move it to the open and closed positions, the said engine power controlled means including a rotary shaft and coöperative intermittently engaging connections for transmitting alternate oscillations to the valve through the rotation of the said shaft, and devices on the rotary shaft for adjusting the said connection whereby to provide predetermined 55 time movements of the valve.

60 2. In a valve mechanism of the character described, the combination with a cylinder, a casing having a valve seat and a port in communication with the compression end of the cylinder above the valve seat, a fluid 65 passage for connection with the intake or

exhaust manifold of the engine and a port in the valve seat in connection with the said fluid passage; of an oscillating valve mounted upon the valve seat, means for holding the valve to the seat, engine power controlled means for intermittently oscillating the valve to move it to the open and closed positions, the said engine power controlled means including a rotary shaft and coöperative intermittently engaging connections for transmitting alternate oscillations to the valve through the rotation of the said shaft, the said engine power controlled means including a double cam mounted upon the valve stem, an engine driven cam shaft, and a pair of cams on the said shaft adapted to successively engage the double cam whereby to first oscillate the cam in one direction and then in the opposite direction.

3. In a valve mechanism of the character described, the combination with a cylinder, a casing having a valve seat and a port in communication with the compression end of the cylinder above the valve seat, a fluid passage for connection with the intake or 90 exhaust manifold of the engine and a port in the valve seat in connection with the said fluid passage; of an oscillating valve mounted upon the valve seat, means for holding the valve to the seat, engine power controlled means for intermittently oscillating the valve to move it to the open and closed 95 positions, the said engine power controlled means including a rotary shaft and coöperative intermittently engaging connections for transmitting alternate oscillations to the valve through the rotation of the said shaft, the said engine power controlled means including a double cam mounted upon the valve stem, an engine driven cam shaft, and a pair of cams on the said shaft adapted to successively engage the double cam whereby to first oscillate the cam in one direction and then in the opposite direction, and devices for adjusting the said cams whereby to provide for predetermined lengths of engagement of the rotary and the double cam devices for timing the valve oscillations.

4. In a valve mechanism of the character described, the combination with a cylinder, a casing having a valve seat and a port in communication with the compression end of the cylinder above the valve seat, a fluid passage for connection with the intake or 110 exhaust manifold of the engine and a port in the valve seat in connection with the said fluid passage; of an oscillating valve mounted upon the valve seat, means for holding the valve to the seat, engine power controlled means for intermittently oscillating the valve to move it to the open and closed 115 positions, the said engine power controlled means including a rotary shaft and coöperative intermittently engaging connections for transmitting alternate oscillations to the valve through the rotation of the said shaft, the said engine power controlled means including a double cam mounted upon the valve stem, an engine driven cam shaft, and a pair of cams on the said shaft adapted to successively engage the double cam whereby to first oscillate the cam in one direction and then in the opposite direction, and devices for adjusting the said cams whereby to provide for predetermined lengths of engagement of the rotary and the double cam devices for timing the valve oscillations.

5. In a valve mechanism of the character described, the combination with a cylinder, a casing having a valve seat and a port in communication with the compression end of the cylinder above the valve seat, a fluid 120 passage for connection with the intake or exhaust manifold of the engine and a port in the valve seat in connection with the said fluid passage; of an oscillating valve mounted upon the valve seat, means for holding the valve to the seat, engine power controlled means for intermittently oscillating the valve to move it to the open and closed 125 positions, the said engine power controlled means including a rotary shaft and coöperative intermittently engaging connections for transmitting alternate oscillations to the valve through the rotation of the said shaft, the said engine power controlled means including a double cam mounted upon the valve stem, an engine driven cam shaft, and a pair of cams on the said shaft adapted to successively engage the double cam whereby to first oscillate the cam in one direction and then in the opposite direction, and devices for adjusting the said cams whereby to provide for predetermined lengths of engagement of the rotary and the double cam devices for timing the valve oscillations.

valve through the rotation of the said shaft, the said engine power controlled means including a double cam mounted upon the valve stem, an engine driven cam shaft, a 5 pair of cams on the said shaft adapted to successively engage the double cam whereby to first oscillate the cam in one direction and then in the opposite direction, and devices for adjusting the said cams whereby to provide for predetermined lengths of engagement of the rotary and the double cam devices for timing the valve oscillations, the said device including means for holding the cams on the cam shaft spaced apart at predetermined distances, whereby to determine the time of contact between the said shaft cams and the double cam on the valve stem.

5. In a valve mechanism of the character described, the combination with an oscillatory control valve, the said valve including 20 a stem and a cam on the stem, said cam having oppositely projected radial extensions; of a cam shaft, a pair of cam disks mounted on and rotatable with the said cam shaft, 25 the said disks each having lateral lugs, the lugs of the two shaft cams being relatively oppositely disposed and adapted for successively and alternately engaging the opposite

extensions of the valve stem and means for adjustably mounting the cams along the 30 shaft whereby to space them wider apart or closer together for timing the oscillations of the valve.

6. The combination with an oscillatable valve having a stem and a cam element on the stem; of a cam shaft having a pair of oppositely acting cams for coöperating with the said valve stem cam, whereby the rotary motion of the cam shaft is converted into an oscillatory motion of the valve stem, 40 and spacing devices for the said cam shaft cams, whereby the degree of oscillation of the valve may be increased or diminished.

7. In a valve mechanism of the class described in which is included an oscillatable valve having at least one port, said valve including a stem, and a cam element on the stem, a removable valve seat including a hollow stem through which the valve stem passes, a rotary shaft, a pair of oppositely 45 acting cams on the shaft that coöperate with the valve stem cam element and means mounted on the removable valve seat stem for restricting the oscillations of the valve stem.

DOMENICO RONCONI.
